UNITED STATES PATENT OFFICE.

EMILE BOURDELLES, OF PARIS, FRANCE, ASSIGNOR TO SCHNEIDER & CIE., OF PARIS, FRANCE, A LIMITED JOINT-STOCK COMPANY OF FRANCE.

WHEELED GUN-CARRIAGE.

1,090,680.

Specification of Letters Patent. Patented Mar. 17, 1914.

Application filed April 15, 1913. Serial No. 761,258.

To all whom it may concern:

Be it known that I, EMILE BOURDELLES, citizen of France, and resident of Paris, France, have invented a new and useful improvement in or Relating to Wheeled Gun-Carriages, which is fully set forth in the following specification.

This invention relates to wheeled gun carriages.

10 Various methods have been proposed for simultaneously increasing the horizontal field of fire and the vertical field of fire of guns on wheeled carriages. Among other solutions it has been proposed to divide 15 the trail longitudinally into two parts which are united for traveling and which can be separated at will in the field; the two semi-trails are pivoted to the gun carriage or to the axle. In any event it is 20 necessary, with a divided trail, to stay the two semi-trails, the stay then constitutes a cross piece which is transverse to the plane of fire and which consequently limits the field of vertical fire.

25 According to the present invention, the gun cradle is mounted in a frame, preferably trapezoidal in shape, the shorter side of which is supported on the axle of the wheeled carriage in such a manner that the 30 frame is enabled to rotate about an axis normal to the axle of the wheeled carriage, while the sides of the frame serve as supports when resting on the ground. The side of the frame opposite the supported side 35 can generally be dispensed with or be constituted by a detachable cross piece coupling the extremities of the supports and forming an anchoring spade. The long sides of the frame may be detachable or in 40 folding sections or telescoping one within the other, but the preferred form is in folded sections. In this manner a rigid frame is formed which is completely open and inside which the gun can assume any desired 45 inclination for vertical aiming. At the same time the supporting polygon is perfectly deformable.

The invention also comprises a practical device for coupling the carriage to the limber the application of this device being particularly applicable to the improved form of carriage. This device consists broadly speaking of a coupling member projecting from the cradle in which the gun recoils.

55 In order that the said invention may be

more clearly understood and readily carried into effect I will now proceed to describe the same more fully with reference to the accompanying drawings in which:

Figures 1 and 2 illustrate one constructional form of the invention in longitudinal sectional elevation and in sectional plan on the line A—A Fig. 1 respectively; the gun, the cradle and its aiming mechanism being omitted in Fig. 2. Fig. 3 is a partial cross section on the line B—B Fig. 1. Fig. 4 is a plan showing the device for coupling the carriage to the limber employed in combination with the improved gun carriage. Fig. 5 is a plan view of a modified constructional form of the frame; Figs. 6 and 7 are sectional detail views showing another embodiment of my invention; and Fig. 8 is a detail view showing detachable side pieces.

In these figures *a* designates the gun carriage axle carrying the wheels *b*.

In accordance with the invention illustrated in Figs 1-3, the body part of the carriage comprises a frame *c—d—d—e*, of quadrangular form, preferably trapezoidal, connected with the axle *a* by a joint which enables the frame to rotate around its longitudinal axis of symmetry. This joint is represented by a pivot pin *f* projecting from the middle of the side *c* of the frame and which is journaled in a bracket bearing *a'* formed on the axle *a*. The side *c* of the frame *c—d—d—e* forms a very compact under carriage and is provided with a stop bearing for receiving a vertical-training pivot *g*. The elevating of the gun takes place around trunnion sleeves *h'* co-axial with a shaft *h—h* in a fork *g'* formed at the upper part of the pivot *g*. The trunnion sleeves *h'* are carried by the cradle *i* in which the gun *j* recoils. The sides *d* of the frame serve as props when their ends rest on the ground and may be provided with spades *d'*, or spades *d''* may be formed on a stay *e* as illustrated diagrammatically in dotted lines Fig. 2.

The mechanism for training and elevating can be arranged in various ways. In the construction illustrated in Figs. 1 to 3, the elevating is effected by means of screw *m*, of the usual construction which bears at one end upon the cradle, and at the other end upon a fork *n* carried by the pivot *g*. The training mechanism comprises a sector

o (Fig. 1) in the form of a rack carried by the under carriage *c* and meshing with a pinion *p* rotating upon a shaft *p'*, which is journaled in an arm *q* carried by the pivot *g*.

5 It will readily be understood that the type of gun carriage that has been described eliminates the usual trail and reduces the portion of the carriage projecting rearward of the pivot *g* to the minimum. In other 10 words the gun can be trained through large angles at the maximum elevation. Owing to the pivotal connection of the frame *c—d—d—e* with the axis *a*, the props *d* can be anchored at different levels according to the 15 nature and profile of the ground upon which the carriage rests. Furthermore, firing can take place under excellent conditions, seeing that the connection between the carriage *c* and the axle *a* permits of a variable penetration 20 of the spades into the ground without tending to cause either of the carriage wheels to lift.

The elimination of the solid trail and the complete freeing of the rear of the pivot *g* 25 enables the gun to be transported with its carriage by means of the special coupling device which constitutes another characteristic of the invention.

As shown in Figs. 1 and 4 the limber and 30 the gun carriage can be brought very close together by means of an engaging device projecting from the cradle *i*. This may comprise a ring *r'* for example, formed upon an arm *r* which is integral with the said 35 cradle *i* and which engages on a hook carried by the limber. In order to facilitate the bringing together of the limber and the gun carriage for coupling together, the props *d* may be telescopic or folding. With 40 this object, these props may be divided transversely into two lengths connected by a hinge *d²* as shown in Fig. 1, and upon the left hand prop *d* in Fig. 2. An appropriate locking device *d³* (Fig. 1) insures the 45 rigidity of the props upon the ground during firing. For transport purposes, the pin or locking latch *d³* is withdrawn and the rear lengths of the props are turned upon the shorter lengths that are integral with the 50 under carriage *c* as shown in Fig. 4. In this manner the gun carriage and the limber as a whole are rendered very compact and can be turned and maneuvered with the greatest ease. As shown in Fig. 5, the folding 55 might also be effected by turning the props around hinges arranged upon the inner faces parallel with the axle. In this case the folded props may be united by a locking device and the rear prop might 60 serve as an attachment to an arm or other coupling member *r*, capable of assuming the two positions indicated respectively in full lines and in broken lines in Fig. 5.

Figs. 6 and 7 show, respectively in partial 65 cross section on the line D—D of Fig. 7 and

in longitudinal section on the line C—C of Fig. 6, another embodiment of the invention. In this second embodiment, the joint between the gun carriage frame *c—d—d* and the axle *a*, with a view to the possible rotation 70 of the latter around the longitudinal axis of symmetry of the said frame, is obtained in the following manner: Upon its upper face, the axle is recessed to form a cup in the form of the arc of a circle *a²* and the under carriage *c* has a suitable projection for sliding or rolling in the cup thus formed. In the example illustrated, the axle *a* is assumed to comprise a central portion of girder formation and the under carriage *c* is provided 80 with a part *c'* which has projections *c²* that fits beneath the upper flanges of the girder. The relative displacement between the cup *a²* and the parts *c¹—c²—c³* of the under carriage *c* is facilitated by the interposition, 85 between the cup and the arm *c'* of rollers *s* which can be guided in one or other of these elements. Mutual guidance can be obtained by means of pinions *t* carried by the rollers and rolling on teeth *a³* formed in the cup *a²*. 90 It will be noted that the virtual axis of articulation is located at the center *z* of the arc *a²*, (Fig. 7).

In both the constructional forms described, the articulation between the frame 95 *c—d—d* and the axle *a*, instead of being obtained by means of a male member carried by the under carriage *c*, movable in a female member formed on the axle, might be obtained by the inverse means, that is to say a 100 projection might be provided on the axle and oscillate in a cup or socket formed on the under carriage *c*. It should also be particularly noted that the gun carriage in the form of a frame *c—d—d* presents, in the 105 firing position, perfect rigidity which facilitates the organization of the aiming mechanisms and considerably reduces the strain on the parts of these mechanisms during firing. 110

The articulation between the frame and the axle, the utility of which during firing has been set forth above, can be locked at will during transport by means of any appropriate locking device, for example of 115 the kind illustrated in Fig. 2. This comprises a spring bolt *u*, carried by the axle *a*, which can be given two positions; a disengaged position in which it is maintained by compressing the spring *u'*, and blocking 120 the head of the rod *u²* upon the box *v* by means of an angularly displaced stud; the other an engaging or locking position, indicated in the drawing, the bolt then being housed in the staple *w* formed in the under 125 carriage *c*.

The props *d* instead of being integral with the under carriage *c*, might, of course, be rendered completely detachable, as shown for example in Fig. 8, a connection 130

by tenon d^3 and mortise c^5 , for example, being maintained for the firing position by means of pins y . The detachable props d might then be connected and transported separately, or fixed in some suitable manner upon the gun or upon the cradle.

In certain cases, the transport of the piece (the gun, the cradle and the carriage) might be effected by coupling with a limber 10 the muzzle of the gun which is provided for this purpose with a coupling member such as a ring, hook or the like engaging in a corresponding member by the limber.

What I claim as my invention and desire 15 to secure by Letters Patent of the United States is:—

1. In a wheeled gun carriage, a gun or gun cradle supporting frame comprising a supporting member articulated to the axle 20 of the carriage and adapted to rotate about a line normal to said axle, and prop members secured to said gun supporting member and adapted to be divergently extended rearwardly into firing position and to be folded up into transporting position.

2. In a wheeled gun carriage, a gun or gun cradle supporting frame comprising a supporting member articulated to the axle of the carriage and adapted to rotate about 30 an axis normal to said axle, and props hinged to said support adapted to swing rearwardly into firing position and to fold forwardly into transporting position.

3. In a wheeled gun carriage, a gun or gun cradle supporting frame comprising a supporting member articulated to the axle of the carriage and adapted to rotate about an axis normal to said axle, props hinged 35 to said support adapted to swing rearwardly into firing position and to fold forwardly

into transporting position, and means for locking said props in firing position.

4. In a wheeled gun carriage, a gun cradle supporting frame and a gun cradle supported thereon, said frame comprising a 45 gun cradle supporting member articulated to said axle and adapted to rotate about an axis normal to said axle, props hinged to said supporting member adapted to swing into firing position and fold forwardly into 50 transporting position, and means on said cradle between said props for attaching the cradle to a limber.

5. In a wheeled gun carriage, the combination of a pair of wheels and an axle in 55 which is located a socket normal to the length of the axle, a gun supporting frame having rearwardly extending arms forming props for the frame, and a cross member having a pivot fitting said socket and a 60 socket for receiving a training pivot.

6. In a wheeled gun carriage, the combination of a pair of wheels and an axle, a gun supporting frame comprising rearwardly extending and diverging folding 65 arms to serve as props for the frame, and a member connecting said arms having an articulated connection with said axle to rotate about a line normal to the axle, a gun cradle mounted to train on said member and 70 provided with means for connecting with a limber brought between said arms when folded over the gun carriage.

In testimony whereof I have signed this specification in the presence of two subscribing witnesses.

EMILE BOURDELLES.
